BATCH SINTERING PLANT

Walter Kelsey, New York, N. Y.

Application April 26, 1948, Serial No. 23,305

8 Claims. (Cl. 266—21)

1

This invention relates to batch sintering plants. The object of this invention is to make possible an economical plant of large capacity for sintering fine enriched ores and smaller plants for the small steel mills, for the disposal of fly ash, and other uses.

In the well known batch sintering plant heretofore used, the term sintering pan includes in the working unit a sintering pan, a grate and a suction chamber, all of which revolve as a whole to dump the finished sinter charge.

Instead of using this known dumping sintering pan, a horizontal stationary grate, a stationary suction chamber below the grate, and a movable U frame having two parallel legs and a joining member with a rear bar or wall completing the mould or frame, for holding the stock to be sintered, are used in the present invention. Said mould or frame is horizontally disposed around the margin and above the stationary grate, and is movable laterally away from the grate. After the grate below this frame has performed its sintering action and the stock has been converted to a sinter and while still held by the mould or frame, the rear bar or wall is displaced and the horizontal U frame is moved horizontally away from the grate, to a breaker roller having spikes to break up the sinter within the frame, said roller being disposed horizontally aligned from the grate to act upon the horizontally moving sinter in the frame. This horizontal frame, when transposed, by suitable mechanism, from its position above the grate to its position below the sinter breaker roller, makes it possible to discharge the sinter cake out of the frame, away from the grate in one operation and at one working level with the formation of the sinter.

This new sinter frame, sinter frame operating mechanism, and breaker roller, is less expensive than the aforesaid dumping sintering pan, and sinter crusher at present in common use, and permits a much more compact combination of equipment units, affording a smaller and less expensive structure. In the present improvement the grate and the suction chamber below the grate, remain fixed and stationary, the only removable parts being the frame and rear bar or wall.

In accordance with common practice, sinter fines and sinter stock of one or more grades is prepared and delivered to the storage tanks above the charge car. From these tanks sinter and sinter tank is run into the charge car which functions to charge each sintering pan as re-

2

quired. The improvement consists in moving the charge car and the hood with the ignition means in directions not in conflict with the direction of movement of the sinter frame.

The improved plant produces less dust than the dumping sintering pan operating vertically, and the improved combination of equipment provides for readily collecting any dust laden air. The treatment of this dust laden air is outside of the direct path of sinter production. Likewise, the gases, products of combustion, from the horizontal side discharge sinter pan, are discharged outside of the direct path of sinter production and can be handled as may be required.

15 More particularly, the improved sinter frame is of U shape, the legs of which are connected with mechanism such as chains passing over sprockets operated from a source of power, which chains move the U frame horizontally to and fro. In the preferred embodiment the U is closed by a vertically movable rear bar or wall to complete the mold or frame around the grate, and this enclosing rear bar or wall is moved out of the path of the U frame and the sinter held 20 therein before said U frame is moved horizontally away from the stationary grate, in side discharge fashion to and under the sinter breaker roller.

25 Air tight connecting members are provided and also means to guide the frame during its horizontal to and fro movement.

The invention will be further described, an embodiment shown in the drawings, and the invention will be finally pointed out in the claims.

30 In the accompanying drawings,

Fig. 1 is a vertical section of a plant embodying the invention taken on line 1—1 of Fig. 2, and seen in the direction of the arrows;

35 Fig. 2 is a partial plan of the plant embodying the invention, as seen from line 2—2 of Fig. 1;

40 Fig. 3 is a partial longitudinal section of the plant embodying the invention, as seen in the direction of the arrows of line 3—3 of Fig. 2;

45 Fig. 4 is a diagram of operating parts to show the horizontal sliding movement of the frame, and breaker roller equipped with spikes so as to break the sinter cake as it is moved horizontally below the roller, as seen from line 4—4 of Fig. 2;

50 Fig. 5 is a vertical diagrammatic section of the air valve shown in Fig. 1;

Fig. 6 is a vertical section taken on line 6—6 of Fig. 2;

55 Fig. 7 is a vertical section taken on line 7—7 of Fig. 6;

Fig. 8 is a plan view taken on line 8—8 of Fig. 6;

Fig. 9 is a vertical section taken on line 9—9 of Fig. 2; and

Fig. 10 is a vertical section taken on line 10—10 of Fig. 2.

Similar characters of reference indicate corresponding parts throughout the various views.

Referring to the drawings, Figs. 1, 2, and 3, the frame 25 has a front frame joining member or wall 26 and two end frame parts or walls 28, generally speaking forming a U-shaped frame. A rear bar or wall 27 is provided to close the open of the U to form a mold. This frame 25 is above and around three sides or margin of the horizontal stationary grate 29, with the rear wall 27 along the margin of the fourth side of the grate, this combination forming a horizontal sintering pan which holds the sinter stock while being sintered. The tops of the three sides of the frame 25 and the top of the rear wall 27, are level and each side has the same height above the grate 29. The grate 29 is supported on a beam structure 29A which is carried by the walls of a fixed suction chamber 79. The top of these suction chamber walls is level with the top of the grate and carry also the bed plates 46A and 47A supporting frame parts 28 and 26 and bed plate 48A supporting rear bar 27. On the bed plates, bearing surfaces for the U frame are provided. The rear bar has a bearing surface which is lower than the bearing surfaces for the U frame, which allows the frame and sinter to move over the bed plate below the rear bar, when it is removed.

A line shaft 42 with clutch connection to sprocket wheel 43, chain drive 40 to sprocket wheel 39 on countershaft 41, (see Fig. 4), rotates the shaft 41. Two drive sprocket wheels 38 are located on the shaft 41 aligned with the end walls 28 of the frame 25. Connections to the rear ends of the walls 28 are made by chains 37 and 37A. The lower part of chain 37 connects to the lower part 44 of wall 28, passes under and around driving sprocket wheel 38, under idler guide wheel 36, thence over top of idler wheel 32, turning under and attaching to the top of and at the end 45 of wall 28. To move the frame 25 rearwardly from its position over the grate 29, the two chains 37 attached to the two wall ends 44 are pulled back by the driving sprocket wheels 38 bringing connections 44 to the position 44A and connections 45 to position 45A. This brings the front wall 26 connected with the front end of the walls 28, to a position away from the grate to the position 26A, which is the full sinter discharging position, (see Fig. 2). The joining member or front wall 26 serves as a platen to discharge the sinter cake. Reversing the direction of driving sprocket wheel 38, the ends of chains 37A connecting to walls 28A at 45A are pulled back by action of the chains around idler wheels 32 to the position 45. This returns the front wall 26 to its position over the grate 29, to act as the pan for the sinter stock, and completes the return of the discharge operating cycle. The frame 25 is kept in position during its movement by the guide wheels 34 and 34A bearing against the frame ends 28.

The part of the grate, the grate bars on which the sinter stock rests and is sintered are placed aligned with the motion of the sinter and the sinter moving frame. This is shown by the views of the grate 29 in Figs. 6, 7, 9, and 10. The ends of these grate bars 29 shown in Fig. 9 are notched so that they will not be forced out of

their bearing by the force of friction of the sinter on the bars.

The plate facing on the inside of each leg 28 of the U frame extends down, as shown by 28C, below the top level of the bearing bar 46 to prevent as far as possible sinter getting on the bearing surface of a zigzag bar 46.

Before the horizontal movement laterally of the grate or the side discharge movement of the 10 frame is begun, the back wall 27 is moved up the guides 30 to the position 27A (Fig. 1), the removal of this back wall 27 permitting the sliding movement of the frame 25 as described. The back wall 27 takes the position 27A to clear the movement 15 of a charge car 50. Any suitable hoisting mechanism for the wall 27 may be provided and is not shown.

The parts of frame 25 and wall 27 being movable, must make when functioning as walls for 20 the stock to be sintered, a fairly air tight joint with the supporting structure bounding the grate. This structure is also the top bounding edge of the suction chamber. The two end walls 28 are made up of adaptable structural shapes finished 25 at top and bottom with plates or bars. These end walls 28 have their weight partly carried on rollers 33 and 35, but at the start of their travel cycle and at the finish the whole weight is carried on the bearing surface of the zigzag bar 46 (see Figs. 6 and 8). This is placed underneath the bottom plate of wall 28 and attached to the bed plate 46A (Fig. 6). This bearing bar 46 is so shaped that any pieces of sinter getting under the bottom plate of wall 28 and on bar 46 will 30 be rolled off of the bar allowing the plate of 28 to rest on the bar with a fairly air tight fit. This type of joint will give long wear before renewal will be necessary. Front wall 26 and back wall 27 are also made up of adaptable structural 35 shapes. The bottom of the front side 26, (see Fig. 7) will come to rest on the narrow raised bearing surface of bar 47 attached to bed plate 47A, giving an air tight joint with little wear. Several pieces 40 26B shaped to ride up on the bar 47, are attached to the wall 26. The bottom of the back wall 27, (Fig. 9) has a wedge shaped bar 48 attached. As the back wall 27 is dropped to position to close the U shaped frame 25, the narrow bearing surface of the bar 48 will cut through sinter on the 45 level bed plate 48A and make an air tight joint. The space between the end walls 28 of the adjacent frames 25 is filled level with the top of ends 28, (see Fig. 6) by a plate 49 which is supported by the extended grate supporting beam structure 50 29A. Sinter stock getting into the pocket between adjacent frames 25 is conveyed by spouting to the fines conveyor.

As stated, the inside faces of the walls forming the pan (the several parts of the frame 25 and 60 the rear wall 27), are in line with the outside lines of the grate. This gives full suction or draft up to the inside face of the walls. However, as a means of reducing the sticking of the sinter to the walls, the draft and the burning at the 65 inside face of the walls is reduced by stopping the grate surface some distance inside of the face of the pan walls, in other words, to have the frame 25 and the rear wall 27, form an enclosing space extending beyond the sides of the grate 29. 70 A prism of sinter stock along the inside face of the walls is formed, as such stock has less draft and is not fully sintered. This is easy to break away from the sides of the walls. The prism of sinter stock defined by points 28B and 29B in Fig. 10, does not get full draft from grate 29.

The end wall 28 bears on the surface of the zig-zag bar 46 supported on its base 46B (Fig. 10). The wall 28 is offset from the suction chamber 79, and a space 96 is formed. A similar space extends inside of the walls 26 and 21, offsetting the walls from the suction chamber 79.

The suction break valve 86 (Fig. 1) gives a means of equalizing the air pressure on the top and bottom of the sinter cake after burning is completed. Holding the sinter cake under equal pressures aids in quenching the fire in the cake by stopping the flow of air. The oxygen in the cake will soon be exhausted when no further supply of air is admitted into the sinter cake.

The sinter breaker roller 31 (Figs. 1 and 4), placed back of the sinter pan 25 and, equipped with spikes 31A is so placed as to engage and break the sinter cake into pieces of the desired size, and is driven by the sinter cake being forced under it. Exceptional conditions may require additional power.

The broken sinter is shoved down across the screen or grizzly 70 and is separated from the fines and dust before it passes through the dust curtain 71 onto the platform 72. The fines flow through hopper 73 upon the fines conveyor 74. Dust laden air is drawn from around the roller 31 and from the dust curtain 71 through the grizzly 70 and the damper 75A into the ducts 75 and 76, through the suction fan 77 and discharged through duct 78 to the dust collectors.

The suction chamber 79 (Figs. 1 and 3) is air tight and the suction produced by the fan 80 is exerted on the whole under side of the grate 29. The bottom of the suction chamber is hopper shaped. The sinter fines falling through the grate are collected and discharged upon the conveyor 74 through a door 87 closing air tight.

Each suction intake 81 (Fig. 1) at the suction chamber connects through a duct with an expansion section 82 and through air valve 83 to the fan suction manifold 84. Connected to this suction duct is the suction break valve 86. To prevent, to some extent, sinter from entering the duct a cover 85 is put over intake 81. Discharged gases in duct 88 are handled as may be required.

The air valve 83, (Figs. 1 and 5) has a gate 89 running in guide 90 and closing against seat 91 with an operating rod 92. The valve body is air tight and has flanges or other means to connect into the duct line. The bottom of the valve body is dropped below the air flow to form a pocket 93 to collect sinter. A baffle 94 directs the sinter down into the pocket. An air tight clean-out door 95 is provided for the pocket.

Operating accessories as known, include the charge car 50 (Figs. 1 and 3) which travels on an elevated track 59 (Fig. 3). One car is used to charge the number of pans generally used in a bank. The car may have several hoppers depending on the way the charge is prepared and bedded. One type of car 50 giving good bedding for the type of sinter pan 25 has two hoppers 53 and 55 suspended in the truck frame having the gates 52 and 54 with discharges at the sintering pan 25 level. The known traversing and operating mechanism, parts of which will be on platforms 56 and 51, is not shown. Hopper 53 is filled with a fine sinter that will be retained on the grate; hopper 55 is filled with prepared sinter stock. The charge is bedded while the car is in motion. A thin layer of sinter is placed on the grate and on this sinter layer is placed the layer of prepared sinter stock. The two hoppers 53 and 55 on the car 50 are filled from storage hoppers 57 and 58.

These materials are prepared and put in these storage hoppers by common and well known means; special top surface leveling mechanisms in the hoppers may or may not be used.

5 The known ignition hood 60 (Fig. 3), above the sintering pan 25, is suspended from the truck 61 traveling on elevated track 59. One hood is used to ignite the pans in the number of pans generally used in a bank. The sinter stock in this 10 type of sintering pan 25 is ignited by a flame in the hood; several burners may be used; two burners 62 are shown. No fuel storage or burner equipment and no traversing equipment is shown and other features making a complete hood are 15 not shown.

From Fig. 3 it is seen that the charge car 50 moves along the track 59 from its position shown in full lines to the position over a sinter frame 25. Also, the hood 60 with its ignition means, is 20 moved by the truck 61, along the track 59. The side discharge movement of the sinter frame 25, in the embodiment shown, is in a direction at right angles to the direction of movement of either the charge car 50 or the hood 60.

25 Practically all of the equipment in the central operating combination is serviced by the traveling crane 65 (Figs. 1 and 3).

Parts of the structure including pieces 66, 67, 30 68 and slab 69 (Fig. 1) are so fabricated as to safely take the stresses developed by the chain 37 pull and the breaker roller 31 reaction.

From the foregoing it is noted that the sinter is broken at a point distant from the grate. After the sinter leaves the breaker roller 31 it is separated from the fines by a grizzly 70 or other screening means and dust is removed before it is discharged into the platform 72 for shipping or further processing. The sinter fines falling through the grate 29 of the sintering pan and 40 the fines screened from the broken sinter collected in hopper 73, are discharged onto a fines conveyor 74 carrying them into the sinter stock preparing part of the plant. The above described equipment combination and process produces a 45 dry sinter, the quenching and dust collecting being accomplished by air.

I wish it to be understood that I do not desire to be limited to the exact details of construction shown and described, for obvious modifications 50 will occur to a person skilled in the art.

I claim:

1. In a batch sintering plant having a stationary horizontally disposed grate, and a bed plate, having its upper surface on a level with the upper 55 surface of the grate and surrounding the grate, the combination of a surrounding frame of end and side walls above the grate having its walls along the margin of said grate for sintering stock to a sinter cake therein while above the grate, bearing bars on said bed plate between said frame and the grate level, and means for moving the frame from above the grate to a position free of the grate.

2. In a batch sintering plant having a stationary horizontally disposed grate, and a bed plate, having its upper surface on a level with the upper surface of the grate and surrounding the grate, the combination of a frame above the grate and surrounding said grate, for sintering stock to 70 a sinter cake therein, while above the grate, means for moving said frame from above the grate to a position free of the grate, said frame having two spaced end walls disposed longitudinally aligned with the direction of movement of said frame when moved away

from the grate to a position free of the grate, and having two spaced front and rear walls transverse to said direction of movement, and bearing bars on said bed plate and attached thereto, below said end walls, said bearing bars having a continuous zigzag contour to provide an airtight self-cleaning contact between the lower surfaces of said end walls and the upper surfaces of the bearing bars, during said movement of the grate.

3. In a batch sintering plant having a stationary horizontally disposed grate, and a bed plate having its upper surface on a level with the upper surface of the grate and surrounding the grate, the combination of a sinter frame above the grate and surrounding the grate, the said sinter frame consisting of a connecting front wall, two end walls forming a U frame, and a back closing wall, the back closing wall having a wedge shaped projection with its apex extending downwardly, means for moving the back closing wall up and away from the U-shaped frame and returning the said back closing wall to its original position, said apex cutting through any sinter on the bed plate giving an air tight contact.

4. The structure of claim 1, in which an end wall of the frame has a rearward extension, and the said means for moving the frame from above the grate to a position free of the grate, include a pair of horizontally aligned vertical sprockets, one driving sprocket at a distance rearward from an extension substantially equal to the length of the end wall of the frame, the other sprocket above said extension, and a chain having one end secured to the lower side of said extension, projecting in line with said end wall passing under and over the driving sprocket, and over and under the other sprocket above the said extension, and secured to the top of said extension, the frame being adapted to be moved from the position over the grate to away from the grate by rotating the driving sprocket in one direction and returned to the original position over the grate by rotating the driving sprocket in the opposite direction.

5. The structure of claim 1 in which the rear side wall is detachable from the frame, means for moving the rear side wall up and out of its position in the horizontal plane of the frame, and outward away from over the grate, and means

to return said wall to its original position in the frame.

6. The structure of claim 1 in which the inside face of each side and end wall of the frame is horizontally spaced outwardly beyond the corresponding margin of the grate forming a marginal area made impervious to the flow of gases.

7. In a batch sintering plant having a stationary horizontally disposed grate, a bed plate along each end and each side of the grate, the upper surface of each end and side parts of the bed plate to be level with the top of the grate, a bearing bar attached to the top of each end part and to the top of the front side part of the bed plate, a grate surrounding U frame consisting of two end and a front side wall rigidly connected together located on said bearing bars, a fourth detachable rear wall for the U-shaped frame to form the sinter retaining frame, a wedge shaped bar on said rear wall, the apex of the wedge shaped bar resting on the rear side bed plate, means moving said detachable rear wall away from the U-shaped frame, and means moving said U frame away from said grate.

8. The structure of claim 1, with means for returning frame to above the grate, a charger for supplying the frame with stock when the frame is above the grate, an ignition hood for igniting said stock, a pair of rails above the frame for the charger and ignition hood, and supports for the rails laterally of the frame, to enable the charger and ignition hood to act within the supports and within the frame, the direction of said rails, and the direction of movement of said charger and ignition hood, being at right angles to the direction of movement of the frame from above the grate to away from the grate and in return.

WALTER KELSEY.
